UNITED STATES PATENT OFFICE

HERMAN F. LEHMAN, OF DAYTON, OHIO, ASSIGNOR TO FRIGIDAIRE CORPORATION, OF DAYTON, OHIO, A CORPORATION OF DELAWARE

REFRIGERATING APPARATUS

Application filed July 31, 1930. Serial No. 471,856.

This invention relates to refrigerating apparatus and more particularly to cabinets employing such apparatus.

Floor space in stores equipped with refrigerated storage cabinets is very valuable and since these stores are now dispensing various food products, some of which are required to be maintained at different temperatures than others, it is one of the objects 10 of this invention to provide an improved cabinet, having compartments therein maintained at different temperatures, and to construct the cabinet so that it will occupy no more floor space than cabinets heretofore used for the storage of products all of which were maintained at the same temperature.

Another object of the present invention is to provide an improved refrigerator cabinet, having at least two compartments formed 20 therein, and to arrange in the cabinet a single evaporator extending into both compartments which will maintain each of the compartments at different temperatures.

Further objects and advantages of the present invention will be apparent from the following description, reference being had to the accompanying drawings, wherein a preferred form of embodiment of the present invention is clearly shown.

30 In the drawings:

Fig. 1 is a perspective view of a refrigerated ice cream storage cabinet constructed according to the present invention;

Fig. 2 is an enlarged top sectional view of my improved cabinet taken along the lines 35 2-2 of Fig. 1;

Fig. 3 is an enlarged vertical section of my improved cabinet taken along the lines 3-3 of Fig. 2; and

40 Fig. 4 is an enlarged top sectional view similar to Fig. 2 showing a portion of a modified form of my invention.

For the purpose of illustration, I have shown my invention embodied in an ice cream cabinet generally designated at 10. The cabinet comprises two compartments 11 and 12 formed by tanks 13 and 14 for holding a quantity of non-congealable liquid or refrigerating medium such as brine 15. The tanks 13 and 14 are surrounded by insula-

tion 16. The inner end wall of each tank 13 and 14 is off-set to provide vertical walls 17 and 18 which extend parallel with opposite end walls of the tanks 13 and 14 and are disposed in different planes. Each tank 55 is also provided with a vertical wall portion 19 which extends parallel with the side walls of cabinet 10 and connects with walls 17 and 18. These walls 17, 18, and 19 provide a partition between the compartments 11 and 12 and may be insulated. One or more cylindrical receptacles 21 may be disposed in compartment 11 and adapted to receive storage cans of bulk ice cream. One or more receptacles 22 may be disposed in compartment 60 12 for receiving and storing ice cream in the form of bricks. Sealing means such as lids 23, which rest on the top of cabinet 10, may be employed to close the openings in the top of cabinet 10 which openings permit 70 access to the interior of the various receptacles 21 and 22.

The insulation 16 which surrounds the tanks 13 and 14 may comprise slabs of cork cemented to the tanks by means of an asphaltic cement. The cabinet top generally designated as 26 may be bolted to the lower portion of the cabinet and may comprise insulating material embedded in wood members. A suitable outside metallic panel 27 may be placed around insulation 16 and an upper metallic cover 28 may be placed over the insulated top 26 of the cabinet. It is to be understood that the tanks, insulation, and outer metallic coverings of the cabinet are supported in any suitable manner by a metal frame 29 of sufficient strength.

One side wall of tank 14 is provided with an opening 31 having a heavy metal ring 32 around the edge thereof and welded to the interior of the tank 14. This ring is adapted to receive bolts 33 which pass through a flange 34 provided on the front of the evaporator 35. The evaporator 35 includes an elongated container 36 which is disposed in compartment 12 and extends into compartment 11 through an opening 37 provided in the connecting wall 19 which forms a part of the partition between compartments 11 and 12. A sleeve 38 secured to the wall of tank 12 may be em- 85 90 95 100 105

ployed to support the end of evaporator 35. The container 36 has a float valve mechanism 25 therein for controlling and maintaining a predetermined level of liquid refrigerant in 5 the evaporator. This float valve mechanism 25 may be of the type disclosed in the patent to Osborn 1,556,708, filed October 13, 1925. The evaporator 35 is provided with refrigerant inlet and outlet connections 41 and 42 for 10 connecting the evaporator to any suitable refrigerant circulating device (not shown). The refrigerant inlet and outlet connections 41 and 42 of the evaporator 35 are located in a space provided by the wood frame 43 in the 15 insulated wall of cabinet 10 and are adapted to be covered by a suitable insulation which is in turn covered by a small removable metal plate 44 which covers the opening 45 provided in the panel 27 of cabinet. I provide a plurality of fins 46 on that portion of container 36 which is disposed in the compartment 12 in order to increase the cooling surface of that portion of the evaporator so as to obtain a lower temperature in compartment 12 than 20 is maintained in compartment 11.

In Fig. 4 I have shown a modified form of my invention wherein the tank 47 of the cabinet 10 is of one piece and a partition 48 is 25 removably secured to the tank by U-shaped brackets 49 so as to divide the tank into compartments 11a and 12a. It is apparent from the disclosure in Fig. 4 that I have provided an ice cream cabinet which may or may not be utilized as a two temperature cabinet. 30 Should it be desirable to maintain the same temperature throughout the entire cabinet the partition 48 may be removed from the cabinet. In order to remove the partition 48, evaporator 35 and the insulated top 26 of 35 cabinet 10 is removed thus permitting the partition 48 to be raised upwardly and removed from the cabinet. After evaporator 35 has been again placed in the cabinet and the insulated top 26 has been placed on the cabinet 40 it is obvious that substantially the same temperature will be maintained throughout the cabinet.

It is apparent from the foregoing description that I have provided a novel refrigerator 50 cabinet employing a single evaporator of a refrigerating system to produce two temperatures in the cabinet for storing various food products such as two varieties of ice cream. Thus my improved cabinet permits ice cream 55 in the form of bricks to be stored in one compartment thereof and maintained in a solid state while at the same time permitting bulk ice cream to be stored and maintained in another compartment of the cabinet at a substantially higher temperature in order to permit the bulk ice cream to be readily dispensed. Furthermore it is apparent that my improved arrangement provides a cabinet 60 which will occupy no more valuable floor space than refrigerator cabinets heretofore 65

employed in which one temperature only was maintained.

While the form of embodiment of the present invention as herein disclosed, constitutes a preferred form, it is to be understood that other forms might be adopted, all coming within the scope of the claims which follow.

What is claimed is as follows:

1. A refrigerating apparatus comprising in combination, a cabinet, an evaporator within said cabinet, said evaporator having means cooperating therewith for maintaining a substantially constant level of liquid refrigerant therein, a partition dividing said cabinet into a plurality of compartments, said partition including portions extending parallel with the end walls of said cabinet and a connecting portion extending parallel with the side walls of said cabinet, said evaporator extending through the connecting portion of said partition so as to be disposed in both of said compartments and arranged to cause the cooling effect produced thereby within one of said compartments to be greater than in the other of said compartments. 90

2. A refrigerating apparatus comprising in combination, a cabinet, an evaporator within said cabinet, said evaporator having means cooperating therewith for maintaining a substantially constant level of liquid refrigerant therein, a partition dividing said cabinet into a plurality of compartments, said partition including portions extending parallel with the end walls of said cabinet and a connecting portion extending parallel with the side walls of said cabinet; said evaporator extending through the connecting portion of said partition so as to be disposed in both of said compartments, means cooperating with a portion of said evaporator for causing the cooling effect produced by said evaporator within one of said compartments to be greater than in the other of said compartments. 95

3. A refrigerating apparatus comprising in combination, a cabinet, an evaporator within said cabinet, said evaporator having means cooperating therewith for maintaining a substantially constant level of liquid refrigerant therein, a partition dividing said cabinet into a plurality of compartments, said partition including portions extending parallel with the end walls of said cabinet and a connecting portion extending parallel with the side walls of said cabinet, said evaporator extending through the connecting portion of said partition so as to be disposed in both of said compartments, fins on a portion of said evaporator for causing the cooling effect produced by said evaporator within one of said compartments to be greater than in the other of said compartments. 110

4. A refrigerating apparatus comprising in combination, a cabinet, a partition dividing said cabinet into a plurality of compartments, said compartments being substan- 115 120 125 130

tially filled with a non-congealable liquid, an evaporator disposed in said non-congealable liquid and having a float valve mechanism therein for maintaining a substantially constant level of liquid refrigerant therein, said evaporator extending into both of said compartments, fins on a portion of said evaporator for causing the cooling effect produced by said evaporator within one of said compartments to be greater than in the other of said compartments.

5 5. A refrigerating apparatus comprising in combination, a cabinet, a partition dividing said cabinet into a plurality of compartments, said partition including portions extending parallel with the end walls of said cabinet and a connecting portion extending parallel with the side walls of said cabinet, said compartments being substantially filled with a non-
10 congealable liquid, an evaporator disposed in said non-congealable liquid and having a float valve mechanism therein for maintaining a substantially constant level of liquid refrigerant therein, said evaporator extending
15 through the connecting portion of said partition so as to be disposed in both of said compartments and arranged to cause the cooling effect produced thereby in one of said compartments to be greater than in the other of
20 said compartments.

25 6. A refrigerating apparatus comprising in combination, a cabinet, a partition dividing said cabinet into a plurality of compartments, said partition including portions extending parallel with the end walls of said cabinet and a connecting portion extending parallel with the side walls of said cabinet, said compartments being substantially filled with a non-
30 congealable liquid, an evaporator disposed in said non-congealable liquid and having a float valve mechanism therein for maintaining a substantially constant level of liquid refrigerant therein, said evaporator extending through the connecting portion of said partition so as to be disposed in both of said compartments, means cooperating with a portion of said evaporator for causing the cooling effect produced by said evaporator within one of said compartments to be greater than
35 in the other of said compartments.

40 7. A refrigerating apparatus comprising in combination, a cabinet, a partition dividing said cabinet into a plurality of compartments, said partition including portions extending parallel with the end walls of said cabinet and a connecting portion extending parallel with the side walls of said cabinet, said compartments being substantially filled with a non-congealable liquid, an evaporator
45 disposed in said non-congealable liquid and having a float valve mechanism therein for maintaining a substantially constant level of liquid refrigerant therein, said evaporator extending through the connecting portion of
50 said partition so as to be disposed in both

of said compartments, fins on a portion of said evaporator for causing the cooling effect produced by said evaporator within one of said compartments to be greater than in the other of said compartments.

55 In testimony whereof I hereto affix my signature. 70

HERMAN F. LEHMAN.
